UNITED STATES PATENT OFFICE.

HOMER M. HOFFMAN, OF PITTSBURGH, PENNSYLVANIA, ASSIGNOR TO PITTSBURGH PLATE GLASS COMPANY, OF PITTSBURGH, PENNSYLVANIA, A CORPORATION OF PENNSYLVANIA.

POLISHING-BLOCK.

1,332,896.

Specification of Letters Patent. Patented Mar. 9, 1920.

Application filed July 17, 1915. Serial No. 40,348.

To all whom it may concern:

Be it known that I, HOMER M. HOFFMAN, a citizen of the United States, residing at Pittsburgh, in the county of Allegheny and 5 State of Pennsylvania, have invented certain new and useful Improvements in Polishing-Blocks, of which the following is a specification.

The invention relates to the blocks used 10 in polishing plate glass, and the primary object of the invention is to provide for a more economical use of the felt employed. The felt pads upon which the polishing rouge is used are expensive and under the 15 present practice are removed when about half worn through to avoid any danger of the pads tearing during the polishing operation and thus permitting the metal of the runner blocks on which the pads are 20 carried to engage the glass and scratch it. My improvement permits the felts to be almost entirely worn through without any danger of scratching the glass. Certain embodiments of the invention are illustrated 25 in the accompanying drawings, wherein—

Figure 1 is a vertical section through a polishing block embodying my invention, Fig. 2 is a bottom plan view of the polishing block of Fig. 1, and Figs. 3 and 4 are 30 vertical sections through the lower portions of modified forms of blocks.

Referring to Figs. 1 and 2; 1 is a metal runner block; 2 is the framework from which the block is supported over the grinding 35 table; 3 is the spindle by means of which the block is mounted for universal movement in order to adjust itself to the surface of the glass over which the block is moved; 4 is a clamp provided with bolts 5 for securing 40 the block to the spindle; 6 is a sheet or pad of felt held in position by means of the clamping ring 7; and 8 is a polishing felt cemented to the lower surface of the sheet 6. It will be understood that the 45 block as just described is one of a large number, usually arranged in three sets, and mounted over the ordinary grinding table, the blocks being free to rotate, and their rotation being caused by the rotation of the 50 grinding table carrying the glass sheet.

Aside from the additional polishing felt 8 as above described the block is precisely the same as heretofore used in the art, the rouge being applied to the felt 6 and such

felt constituting the polishing element instead of the felt 8. This arrangement involved a considerable waste of felt as it was necessary to replace the felt 6 when it was about half worn through in order to avoid any danger of the felt tearing and the iron 60 1 coming in contact with the glass and scratching it. Furthermore the bending of the felt at the edges of the block 1 caused undue wearing at these points, the felt being about $\frac{1}{8}$ of an inch thick and relatively 65 stiff.

The use of the felt 8 cemented to the bottom of the other felt greatly increases the economy in the use of the felt since the felt 8 can be worn almost through before it becomes necessary to replace it. The impervious rubber cement which is preferably employed sinks into the felt, a slight distance, not over $\frac{1}{8}$ of an inch, and it is necessary to remove the felt when worn down to this 75 layer of cement, but the waste involved is obviously relatively slight as compared with that of the old procedure. Another advantage incident to this construction lies in the fact that scrap felt may be employed in 80 making up the pad 8, Fig. 2 illustrating how corner sections can be utilized for this purpose. This use of built-up felts was of course not possible with the arrangement as heretofore employed wherein the felt was 85 held only at its edges by the ring 7. The felt 8 also wears uniformly since it is perfectly flat and there are no corner portions tending to bulge down as was the case with the felt as heretofore used. Since the pad 90 6 is not used for polishing purposes, some other, and less expensive fabric may be used, if desired.

Fig. 3 illustrates a modification in which 95 1' is the metal runner block, 6' is a backing pad secured to the runner block, and 8' is a polishing felt cemented to the lower side of the pad 6'. The pad 6' may be secured to the block 1' by means of cement or in any other manner and the composition 100 of such pad may be either felt or any other yielding material. The cement between the sheets 6' and 8' is indicated by the heavy lines 9 which extend inward from the edge a relatively short distance. The central 105 portion of the felt 8' is preferably not cemented to the pad 6' as it is desirable to have the major portion of the felt more

or less free to yield laterally somewhat. This yielding is permitted in the construction of Fig. 1 by reason of the fact that the felt 6 is supported only at its edges.

5 Fig. 4 illustrates still another modification in which 1" is the runner block, 6" is the yielding backing pad, and 8" is the polishing felt. The backing pad 6" is in this instance made of a rubber composition held in 10 place by screws 10. To add to the security the pad may also be vulcanized or cemented to the lower side of the block 1". The felt 8" is secured to the lower side of the pad 6" by means of cement applied either at the 15 edges as in the construction of Fig. 3 or over the entire upper surface of the felt. Various other arrangements might obviously be employed for carrying out the invention, but the foregoing will be sufficient to illustrate 20 the principle of construction involved and the breadth of the invention.

What I claim is:

1. In combination, a plate glass polishing block comprising a metal runner block, a 25 pad of yielding material secured on the

lower surface of the runner block, and a disk of polishing felt cemented to the lower surface of the pad, and lying throughout in a horizontal position.

2. In combination, a plate glass polishing 30 block comprising a metal runner block, a sheet of polishing felt mounted on the lower surface of the runner block with its edge turned up along the sides of the block, clamping means for securing the turned 35 up edge to the block, and a sheet of polishing felt cemented to the lower surface of the first sheet, and lying flat throughout its area and in a horizontal position.

3. In combination, a plate glass polishing 40 block comprising a supporting block, a pad of yielding material secured on the lower side of the supporting block, and a sheet of polishing felt having its upper surface cemented over substantially its entire area 45 to the pad of yielding material, and the entire sheet of felt lying in a horizontal position from the center to the extreme edge of the sheet.

HOMER M. HOFFMAN.
